UNITED STATES PATENT OFFICE

JOSEPH A. PETERSON AND CARL E. OLSEN, OF HOUSTON, TEXAS

TONG

Application filed June 30, 1931. Serial No. 547,825.

This invention relates generally to tongs and specifically to chain tongs.

A tong of this general type includes a chain, and a handle connected thereto and 5 movable back and forth to effect rotation of the pipe or other work to which it is applied.

A pipe to be rotated is seldom in an open space where the tong handle can be swung through any desired arc. Ordinarily, the 10 pipe is surrounded by adjacent objects so that the tong can be swung back and forth only through a very small arc. This invention has for one of its principal objects the provision of a tong embodying new and im- 15 proved means whereby its chain is automatically held taut on the pipe so that when the handle is swung in a forward direction there is no lost motion, the pipe being immediately gripped and turned; and whereby the chain 20 is immediately slackened and slips about the pipe when the handle is swung in the reverse direction, so that a new gripping engagement may readily be effected.

Another object of the invention is the pro- 25 vision of a new and improved securely gripping tong that will not crush, distort or cut the pipe to which it is applied.

A further object of the invention is to pro- 30 vide a new and improved tong that may be applied to pipes of various sizes.

Various other objects will hereinafter appear.

The preferred embodiment of the invention is illustrated by the accompanying drawings, of which Fig. 1 is an end view with the chain broken and one of the jaw teeth removed; Fig. 2, a fragmentary sectional side elevation illustrating the application of the 35 tong to a pipe; Fig. 3, a fragmentary top plan view of the tong applied to a pipe; Fig. 4, a side elevation of the tong applied to a pipe; and Fig. 5, a fragmentary side elevation of a modified form of the tong applied 40 to a pipe.

Referring first to Figs. 1 to 4 inclusive, the handle is indicated at 1 and the jaw at 2. The jaw is substantially V-shaped, and comprises a pair of spaced pipe-engaging sections 3, each of which has thereon a serrated

tooth 4. The sections 3 are joined together by cross pieces 5 and 6.

The handle 1 extends between the sections of the jaws and is pivoted to the base of the jaw as indicated at 7. In one arm of the jaw 55 and in each of the sections 3 is a socket 8 in a flange 9. These sockets 8 are adapted to receive the ends of any one of the pins 10 connecting the links of the chain 11, whereby the chain may be connected to the jaw 2. 60 The handle 1 has an extension 12 slotted as indicated at 13 for the reception of the chain and having a pair of bores as indicated at 14 for the reception of the ends of any one of the pins 10 of the chain whereby the chain 65 may be connected to the handle. It will be noted that the chain is connected to the extension 12 at a point between the connection of the chain and jaw at 8 and the pivot 7 of the jaw. 70

The handle has an arcuate slot 15 and a pin 16, carried by the jaw, extends through this slot. The handle has a chamber 17 in which is a compression spring 18 to cause the plunger 19 to bear against the pin 16. 75 The movement of the jaw on its pivot 7 is limited by the engagement of the handle bumper 20 and jaw cross piece 6; and by the engagement of the handle extension 12 and the jaw cross piece 6, so that the end walls 80 of the arcuate slot 15 in the handle 1 cannot engage the pin 16 of the jaw.

The operation of the tong may briefly be described as follows:

When the tong is applied to the pipe, the 85 handle is moved with respect to the jaw to compress the spring 18. Then the chain is passed about the pipe, and its end is pulled until it is taut, and the ends of one of the pins 10 is then placed in the sockets 8 of the 90 jaw. When the handle is released, the spring serves to hold the chain taut and to hold the jaw in contact with the pipe. When it is desired to turn the pipe, the handle is swung in a forward direction (downwardly, Figs. 95 2 and 4). The chain and the teeth 4, being already in contact with the pipe, are immediately moved into gripping engagement therewith, and the pipe is turned.

When it is desired to secure a new grip 100

on the pipe, the handle may be swung in a reverse direction, (upwardly, Figs. 2 and 4) whereupon the chain is immediately slackened, and the teeth 4 release the pipe, be-
 5 cause the extension 12 is moved downwardly against the resistance of the spring 18. As soon as the handle is released, the spring 18 functions to draw the chain taut and to move the jaw teeth into contact with the pipe, so
 10 that the handle may again be swung in a forward direction to immediately turn the chain. It will be apparent that the chain may also be slackened by pulling the handle in a direction away from the pipe; and so
 15 the handle may be pulled away from the pipe and at the same time swung in a forward direction without turning the pipe, and when the desired position is reached the handle may be released to permit its movement back to-
 20 ward the pipe to permit the chain to again become taut, after which the forward movement of the handle may be continued to cause turning of the pipe.

The pins 10 of the chain extend laterally
 25 from the links, and so any one of these pins may be placed in the recesses 8, according to the size of the pipe to be turned. Should the permanent connection of the chain to the handle extension 12 become broken, a new con-
 30 nection may readily be effected without dis-
 turbing any of the other parts of the tong because the extension is outside of the jaw, and any one of the pins 10 may be placed in the bores 14. The use of special chain
 35 sections to connect the chain to the handle and jaw is, therefore, avoided.

Figs. 2 and 4 show the handle bumper 20 and the jaw cross piece 6 in contact. This will not occur until an excessive turning force
 40 is applied to the handle. Ordinarily, the bumper 20 is out of contact with the cross piece 6 to permit tightening of the chain into gripping engagement with the pipe.

The turning of the pipe is effected prin-
 45 cipally by the friction between the chain and the pipe. The chain is in contact with very nearly the entire periphery of the pipe, and the pull on the chain is tangential to the pipe. The jaw engages the pipe at the meet-
 50 ing ends of the chain. And so, the teeth 4 do not appreciably cut into the pipe and there can be no crushing or objectionable distortion.

No strain is placed upon the pin 16 be-
 55 cause the handle engages the cross piece 6 to prevent the end walls of the slot 15 from coming into contact with said pin.

The cross piece 5 is placed at a point where the greatest strain on its arm of the jaw occurs.

60 The spacing of the jaw sections and the dis-
 position of the chain therebetween, provides a well-balanced tong. When the tong is ap-
 plied to an annular flange on pipe fittings and the like, the jaw sections straddle the flange
 65 and the chain securely grips it.

Fig. 5 illustrates a modification of the tong shown by the other figures. The modified tong has a special jaw 22 having an arcuate surface 23 to fit a pipe of a given size. This tong will be found particularly useful in 70 turning pipes that are easily distorted and cut, because the surface 23 will serve to support the pipe and there is no biting action whatever.

While the tong provided by this inven-
 75 tion is especially useful on pipes, it will also be found very useful on various other work.

We claim:

1. A tong having a handle; a jaw pivotal-
 ly mounted on said handle; a pipe-engaging
 80 chain connected to said jaw and to said han-
 dle; said handle having an arcuate slot; a
 pin carried by said jaw and movable in said
 slot; and a spring-pressed plunger carried by
 85 said handle and bearing against said pin
 to automatically cause relative movement of
 said jaw and handle to tighten said chain on
 the pipe to which it is applied; said jaw and
 handle having engaging means to prevent
 90 contact between said pin and the end walls of
 said slot.

2. A tong comprising a jaw having a pair
 of spaced sections, each of said sections hav-
 95 ing a pipe-engaging tooth; a handle extend-
 ing between and pivotally connected to the
 rear portion of said sections; a chain con-
 nected to the forward portion of said handle
 and extending between said sections to be
 placed about a pipe and connected to the for-
 ward portion of said sections; a pin carried
 100 by said jaw; and a spring-pressed plunger
 carried by said handle and bearing against
 said pin to automatically cause relative move-
 ment of said handle and jaw to tighten said
 chain on said pipe; said handle and jaw be-
 105 ing provided with means to prevent engage-
 ment of said pin by said handle; said han-
 dle being movable to cause gripping engage-
 ment of said pipe by said chain and teeth.

In testimony whereof, we hereunto affix
 110 our signatures.
